BREAK-AWAY TYPE CLOSURE FOR A CONTAINER

Vincent G. Biedenstein, Overland, Peter J. Ditto, St. Ann, and Harry H. Ellerbrook, Woodson Terrace, Mo., assignors to R.C. Can Company, Overland, Mo., a corporation of Missouri

Filed Sept. 24, 1962, Ser. No. 225,454
6 Claims. (Cl. 220—54)

This invention relates to a break-away type closure for a container, and more specifically to a container closure preferably of a flexible plastic, such as polyethylene, so constructed as to be initially fractured at a predetermined line of weakness near its perimeter by applying a force in one direction and subsequently torn away by a force on the closure in approximately the opposite direction.

For many years, products of petroleum, or the like, have been merchandised in cans of various sizes and shapes and made of metal or of fiber. At the present time, there are several cans on the market which use a frangible type of closure opened by a tool of some kind.

It is the principal object of this invention to provide a frangible closure for a can which can be removed without the use of tools of any kind.

It is a further object of this invention to provide a liquid tight end on a can which has a break-away closure part.

It is a further object of this invention to provide a can end with a break-away closure part which has the necessary strength to withstand internal pressure without fracture or seepage, but which may be opened without tools by a simple manual manipulation of a pull tab of novel characteristics.

It is a further object of this invention to provide a can end closure of the break-away type with a means of operation which is small and compact so as to be readily recessed in the can end.

It is still a further object of this invention to provide a break-away type of closure for a can which is able to resist considerable strain applied thereto but which can be easily operated by small forces applied in a particular way and in a particular sequence.

According to this invention, a can end is closed by a can end closure permanently secured to the rim of the can around its open end in any suitable manner to form a liquid tight joint. The can end closure in turn has an end wall scored to provide a line of weakness which surrounds the perimeter of a break-away cover part. Located on the top of the cover part adjacent a portion of the score is a pull tab with one end secured to the cover part adjacent, but inside, the score line and with its free end extending across the cover part. The pull tab can be relatively stiff or relatively flexible, but, if of flexible material, it is made with a thumb piece at its secured end. The thumb piece is not absolutely necessary if the tab is made of inflexible material and relatively stiff.

In either case, the construction of the pull tab is such that as the tab is gripped between thumb and forefinger and rocked toward the score line, an inwardly directed force is applied to the cover part locally, adjacent the score line, which produces initial break-away. Thereafter, only a very moderate amount of pull is necessary to completely separate the cover part from the can end closure. During this separation, the cover is flexed as it is peeled away, and a tearing action takes place along the score line, thus, minimizing the effort required by concentrating the shearing action as the separation progresses. Because of the construction of the pull tab, the break-away action is far more effective than can be obtained by a simple outwardly directed pull on the tab. As a result, the closure can be constructed far stronger

2

to resist the expected forces which might normally be applied to, or which might accidentally be applied to, the can.

Consider, for example, the advantages in the use of this device on one end of a grease cartridge. Whereas, it would be next to impossible for a mechanic with greasy fingers to grip and remove the cover part by direct pull on the tab, tests have demonstrated that the rock and pull tab described make the break-away type of cover readily operable and far more convenient than those of the type requiring a tool to open. It is recognized that the principle described here resembles that heretofore applied in the construction of tear strips in metal cans, but, so far as is now known, the described application here, the described use here, and the described results obtained from this use and application are believed novel.

Other objects and advantages of this invention will appear in the following detailed description which is in such clear, concise and exact terms as will enable any person skilled in the art to make and use the invention when taken with the accompanying drawings, forming a part thereof, and in which:

FIG. 1 is a side elevation in section of the top part of a can equipped with a closure constructed in accordance with this invention;

FIG. 2 is a top plan view of FIG. 1;

FIGS. 3, 4 and 5 are schematic views illustrating operation of the closure shown in FIGS. 1 and 2;

FIG. 6 is an elevational view in section illustrating a modified form of the invention;

FIG. 7 is a side elevational view in section illustrating another modified form of the invention having a relatively flexible tab as in the prior embodiments;

FIG. 8 is a side elevational view in section illustrating another modified form of the invention having a relatively stiff tab;

FIGS. 9 and 10 are operational views of the form of invention shown in FIG. 8;

FIG. 11 is a top plan view of FIG. 8; and

FIG. 12 is a fragmentary sectional view on an enlarged scale showing a modification which may be used with all forms of the invention shown in the preceding views of the drawings.

Turning now to FIG. 1, a can body 10 is surrounded by cylindrical can walls 11 to form a container. The lower end of the container may be closed by any suitable type of closure and the wall 11 formed of either metal or fiber. The closure, according to this invention, is secured to the top open end of the container around the rim thereof. This can end closure is generally indicated by the reference character 12 and includes a metal cover part 13 of circular form having its outer edge 14 crimped onto the rim of can end wall 11. Can end closure 13 has a central aperture surrounded by a bead 15 which is rolled onto a rim portion 16 of a break-away cover part 18.

The break-away cover part 18 is preferably made of a flexible material, such as polyethylene, and comprises a cover part 18 surrounded by an upstanding rim 16. The rim 16 is tightly clinched by the rolled edge 15 of the can end closure 13. Cover part 18 is surrounded by a score, such as 20, at the periphery thereof between the cover part 18 and the upstanding rim 16. Preferably, the score 20 is made opposite the corner 21 between the break-away cover part 18 and the upstanding rim. The rolled edge 15 of the can end closure 13 is formed so as to provide a depending lip 22 extending adjacent to the score line 20 on the opposite surface of the break-away cover part 18. In the form shown, the can end closure 13 is of sheet metal, and, consequently, the rolled bead 15 forms a rigid support at the periphery of the break-

away cover part which is relatively non-yielding. This feature of the construction contributes to the successful performance of the break-away cover part since it holds the rim of the flexible break-away cover part 16 against any yielding when a force is applied on the pull tab 25.

The pull tab 25 is secured to the outside surface of the break-away cover part 18 adjacent its score line 20 and extends across the break-away cover part 18 from the point or zone in which the pull tab 25 is secured. Formed integral with the pull tab 25 is an upstanding thumb piece or rib 26 which is positioned closely adjacent to the score 10 20 which forms the line of weakness at the perimeter of the break-away cover part 18. The surfaces of the pull tab 25 may be suitably corrugated to obtain a firm finger grip.

As shown in FIG. 2, the arrangement of the thumb piece 26 with respect to the pull tab 25 is such that when the latter is gripped between the thumb and forefinger, the end of the thumb will naturally press against the rib-shaped thumb piece 26.

As shown in FIGS. 3-5, the manner in which the tab is naturally gripped between the fingers produces the desired forces for the successful operation of the action of separating the break-away cover part 18 from the can end closure 13. As shown in FIG. 3, tab 25 is gripped 25 between the thumb and forefinger with the thumb against the thumb piece 26. The hand of the operator is then moved in the direction of the arrow A in FIG. 3 to the position shown in FIG. 4. The rocking motion of the fingers produces a downward force in the direction of the arrows B producing the initial fracture along the line of weakness 20. After the initial fracture, the hand is moved in the direction of the arrow D, as shown in FIG. 5, which will peel the cover part 18 along the line of weakness 20 completely severing the break-away cover 30 35 part 18 from the can end closure 13.

In the modified form of the invention shown in FIG. 6, corresponding parts are indicated by the same reference character with 100 added. In this modification, the break-away cover part 118 is surrounded by an upstanding rim 116 which has an outside diameter snugly fitting within the rim of the can wall 111. The metal bead 114 is clinched to the rim of the can wall 111 at its outer periphery and to the upstanding rim 116 at its inner periphery fastening the closure securely to the open end of the can body 110. The operation of the modification shown in FIG. 6 is the same as that above described. The preferred location for the score line 120 is opposite the corner 121, but it can be located adjacent the corner as in FIG. 6.

In the modification shown in FIG. 7, parts corresponding with those in the prior embodiments are indicated by the same reference character with 200 added. The modification, shown in FIG. 7, differs only in the shape of the thumb piece. The tab is a flexible strip, as in prior devices, and the thumb piece 226 is a plurality of ribs or corrugations instead of a single rib. Otherwise, the same description applies to the parts in FIG. 7 as in the previous illustrations in the drawings.

In the modification shown in FIGS. 8-11, parts corresponding generally and exactly with those in the prior forms are indicated by the same reference character with 300 added. FIGS. 8-11 show a form of the invention heretofore described as having a tab of relatively stiff material, or relatively inflexible in construction. The tab, therefore, is shown at 325 of thicker section as compared to parts 25, 125 and 225. Furthermore, the portion 326 is thicker and, therefore, stiffer so as to form a relatively stiffer connection between tab 325 and the break-away cover part 318.

As shown in FIG. 9, a lifting force at the free end of tab 325 flexes the cover part 318 due to the stiffer connection at 326 and produces an oppositely directed downward force at the end of 326 at the score line 320. This force alone, or in conjunction with thumb pressure, is

enough to produce a local fracture at the score line 320 adjacent the end of portion 326. Thereafter, the pull exerted on the tab 325 tears the closure along the score line to completely separate the tear top 318.

The successful operation of any of the above described forms of the invention depends upon flexibility of the material in the tear top 18 and the rigidity contributed to the tear top 18 adjacent the score line 20 by bead 15. It has been discovered that these features produce concentration of the forces applied by pull on the tab to a focal point on the score line and make initial fracture possible by the application of reasonable manual force to a closure with sufficient strength to withstand shipping and handling stresses. If the tear top 18 is not flexible, or the outer edge by the score line 20 is not inflexibly held, the forces required for fracture and removal become so great that a man of ordinary strength cannot always exert the manual force required. Thus, the advantage of easy opening without tools is lost and the device loses its competitive advantage with other forms of frangible closures. These two features of the closure also contribute to removal after local fracture. If the tear top 18 is not readily bendable, it will not tear easily along the score line 20 and it will not tear at all unless the edge 16 is held rigidly.

In the modification shown in FIG. 12, corresponding parts are given the same reference character with 400 added. With respect to all forms, the score lines 20, 120, etc., are located opposite the corners 21, 121, etc. This may also be true of the form shown in FIG. 12, however, the upstanding rim 416 may also be provided with a score line, such as 430 as in FIG. 12, opposite the free edge of the bead 415 so that upward pull on the tab will cause the flexible closure to buckle at the corner 21 and fracture at the score line when bent around the sharp free edge of bead 415. Thus, if one unfamiliar with the manner of operation of the tear top 418 should exert merely a straight pull rather than the push pull action intended, the closure would fracture anyway. This is so because a straight pull on tab 425 would press the sharp edge of metal at the free edge of the bead 415 into a weakened portion of the plastic closure. This will cause the initial fracture, and, as the flexible plastic is bent against this metal edge progressively, it will continue to tear around the bead 415 to fully separate.

Changes in and modifications of the construction described may be made without departing from the spirit of our invention or sacrificing its advantages.

Having thus described the invention, what is claimed 50 and desired to be secured by Letters Patent is:

1. In a closure for a container having an open end with said closure secured permanently to said open end by means forming a liquid tight joint, and a flexible plastic break-away cover part defined by a means forming a line of weakness in the material of said closure surrounding said cover part, the improvement comprising,

- (1) a flexible finger operated pull tab of plastic material located on the outside of said cover part having one end secured to said cover part adjacent to a portion of said line of weakness and its free end projecting across said cover part away from said portion toward another portion of said line of weakness, and
- (2) means at the secured end of said flexible pull tab operative when said pull tab is grasped between the fingers of the user and its free end lifted away from the outside of said cover part to create a force acting on said cover part in the opposite direction to produce initial fracture in said closure at said portion of said line of weakness.

2. In a closure for a container having an open end with said closure secured permanently to said open end by means forming a liquid tight joint, and a break-away cover part of flexible, rubber-like plastic material defined by a means forming a line of weakness in the material

of said closure surrounding said cover part, the improvement comprising,

- (1) a flexible, finger operated pull tab located on the outside of said cover part having one end secured to said cover part adjacent to a portion of said line of weakness and its free end projecting across said cover part away from said portion, toward another portion of said line of weakness, and
- (2) a thumb piece at the point of attachment between said pull tab and said cover part operative when said pull tab is grasped between the fingers of the user and its free end lifted away from the outside of said cover part to create a force acting on said cover part in the opposite direction on said line of weakness to produce initial fracture in said closure at said portion of said line of weakness.

3. In a closure for a container having an open end with said closure rigidly secured in a permanent manner to said open end by means forming a liquid tight joint, and a break-away cover part of flexible, plastic material defined by means forming a line of weakness in the material of said closure surrounding said cover part, the improvement comprising,

- (1) a flexible, finger operated pull tab located on the outside of said cover part having one end secured to said cover part adjacent to a portion of said line of weakness and its free end projecting across said cover part away from said portion toward another portion of said line of weakness, and
- (2) means including a protruding thumb piece at the attached end of said pull tab operative when said pull tab is grasped between the fingers of the user and its free end lifted away from the outside of said cover part to create a force acting on said cover part at said line of weakness in the opposite direction to produce initial fracture in said closure at said portion of said line of weakness.

4. In the combination of a container having an open end, the improvement comprising,

- (1) a cover part made of flexible material capable of bending and including,
- (2) a rim portion surrounding said cover part formed of the same bendable material,
- (3) a ring-shaped metal part secured to the open end of said container at its outer edge and having a rolled bead at its free inner edge crimped on said rim portion to form a rigid support against bending,
- (4) a score line forming a weakened section in said cover part adjacent said rolled bead for defining a line of fracture between the bendable and non-bendable portions of said cover part, and
- (5) a pull tab attached to said bendable cover part adjacent said score line and operative when tensioned to produce bending of the bendable material in said cover portion with respect to the rigidly supported rim portion and fracture along said score line.

5. In the combination of a container having an open

end, and a tear away type of closure secured to said open end, the improvement comprising,

- (1) a cover part made of flexible material capable of bending and including,
- (2) a rim portion on said cover part formed of the same bendable material,
- (3) a ring-shaped metal part secured to the open end of said container at its outer edge and having a bead at its free inner edge crimped over said rim portion to form a rigid support against bending, and a sharp shearing edge disposed at the edge of said cover part,
- (4) a score line forming a weakened section in said cover part adjacent said bead for defining a line of fracture, and
- (5) a pull tab attached to said bendable cover part adjacent said score line and operative when tensioned to produce bending of the bendable material in said cover part adjacent said tab against said sharp shearing edge and initial fracture along said score line in said cover part at said pull tab.

6. In the combination of a container having an open end and a tear away type of closure secured to said open end, the improvement comprising,

- (1) a cover part made of flexible material capable of bending and including,
- (2) a rim portion around said cover part formed of the same bendable material,
- (3) a ring-shaped metal part secured to the open end of said container at its outer edge and having a rolled bead at its free inner edge crimped on said rim portion to form a rigid support against bending,
- (4) a score line forming a weakened section in said cover part adjacent said rolled bead for defining a line of fracture between the bendable and non-bendable portions of said cover part,
- (5) a pull tab attached to said bendable cover part adjacent said score line and operative when tensioned to produce bending of the bendable material in said cover part with respect to the rigidly supported rim portion to tear said cover part from said rim portion after initial fracture along said score line, and
- (6) means on said bendable closure part positioned at said score line to be pressed inwardly of said container when said tab is grasped and lifted and operative to produce initial fracture along said score line.
